COMBINED SWITCH AND FUSE.

1,138,857.

Specification of Letters Patent. Patented May 11, 1915.

Application filed August 20, 1913. Serial No. 785,660.

To all whom it may concern:

Be it known that we, RALPH ELSMAN and CHARLES DALLERUP, citizens of the United States, residing, respectively, at San Francisco, in the county of San Francisco and State of California, and at San Rafael, in the county of Marin and State of California, have invented new and useful Improvements in Combined Switches and Fuses, of 10 which the following is a specification.

It is the object of the present invention to provide a fuse supporting structure, suitable for use in the protection of electrical circuits of high voltage and combining the 15 fuse device with a switch mechanism, whereby the fuse element may be entirely disconnected from the line when it is to be replaced or adjusted. The structure is preferably so constructed as to be adapted for 20 interrupting a plurality of conductors simultaneously, as for instance the three conductors of a poly-phase circuit and is of a construction easy to manufacture and install and well suited for use in the open 25 air where the weather conditions are severe. By eliminating the fuses from the structure, it may be converted into a simple sectionalizing switch, as hereinafter explained.

Other features and advantages will be 30 apparent from the following description, which is to be taken in conjunction with the drawings, wherein—

Figure 1 is an elevation of the pole top showing one embodiment of the present invention as applied to a three phase transmission line. Fig. 2 is a side elevation of the same. Fig. 3 is a detail of one of the switch blades. Fig. 4 is a detail of one of the fuse clips, and Fig. 5 shows the locking arrangement at the lower end of the reach bar used for controlling the switches.

In the structure illustrated by the drawings, the pole 1 carries cross arms 2, 3, the uppermost of which carries three insulators 4, each of which is surmounted by a metal cap 5 suitably attached, as by cementing, or spinning in at the edges. Each of these caps carries a stud bolt, provided with a wing nut 6 under which an electric conductor may be clamped. This conductor may be connected with a high voltage transmission line. Each metal cap 5 also carries a pair of spring clips 7 serving as switch contacts between which a blade is inserted 55 when the switch is closed.

The bolts 8 whereon each insulator 4 is mounted pass through the top cross arm 2 and also through the end of a metal strip or bracket 9, the lower end of which is bolted to the lower cross arm and the intermediate portion of which is twisted around at right angles to the end portions so that the strip may serve as a bearing member for the movable parts of the switch mechanism.

The switch mechanism comprises switch- 65 ing elements rigidly mounted on an operating shaft or rock shaft 10, which may be in the form of an iron pipe passed through holes in the braces 9 and having a rotating motion with respect to those braces. This 70 rock shaft is preferably provided with a rearwardly extending pipe 11. (See Fig. 2) carrying a counter-weight 12 adjustable thereon and pivotally connected with a reach rod 13 of insulating material, as wood 75 properly treated. It is by operating this reach bar up and down, that the switch and fuse mechanism may be thrown into or out of action. The reach bar 13 passes freely 80 through a retaining strap 14 and is provided with a stop-plate 15 bent up at either end to strike against strap 14, thereby to limit the up and down movements of the reach bar. The lower end of the reach bar is provided with a hasp 16 and pad-lock so 85 that the switches may be locked either open or closed as desired. It will be understood that the reach bar is long enough to be easily accessible when the operator is at a safe distance from the line wires, as for instance 90 when standing on the ground.

The switch mechanism in the particular embodiment here illustrated comprises three members carried by the rock shaft 10 and each made up of an arm 17 which may be 95 iron tubing bent up at one end to form a support for an insulator 18, and rigidly attached at the other end, as by screw-threaded engagement and by clamping bolts, to a casting 19 rigidly attached to the rock shaft 100 10 and also serving as a support for a nipple or pin 20, whereon a second insulator 21 is permanently mounted. Insulator 18 carries a metal cap 22 as shown in Fig. 3 cemented or spun into permanent relation therewith 105 and tapped out to receive stud bolts 23 under which is clamped the flattened end of a switch arm 24, the upper end of which is slotted to receive a switch blade 25 adapted for insertion between the resilient 110

switch jaw clips 7 of the stationary insulator 5. Cap 22 also carries a stud bolt 26, which, as shown in Fig. 4 is used for securing the clip 27 for the fuse. This clip may 5 be provided with a retaining bolt 28 and in accordance with common practice is used to clip the upper end of a removable fuse tube 29, wherein is mounted a fuse adapted to blow and open up the circuit when a dangerous 10 or abnormal current flows through the conductors or apparatus to be protected. The other end of the fuse tube is similarly clamped at the cap 30 of insulator 21 and that cap is provided with a stud bolt having 15 a wing nut 31, whereby a conductor may be attached for connection to the circuit to be protected.

With the reach bar down as shown in Fig. 1 all three of the switch blades will be 20 in contact with their clips 7 and current coming in to the insulators 4 will pass through the switch blades and through the fuses to the caps 30 and thence on to the load circuit. The potentials may be high, 25 higher than eleven kilovolts and the load may be of the character so frequently found in the West, where alternating current motors are used extensively for irrigation and reclamation purposes. In case of an abnormal 30 current through the device here shown, as for instance in case of short circuit at the motor, one or more of the fuses will blow, interrupting the circuit and protecting the line from the abnormal conditions. The 35 operator may then thrust the wood reach bar upward, thereby swinging the rock shaft 10 and opening up the switches simultaneously and by a distance far enough to make it safe for the operator to then replace 40 the fuses and to otherwise make such examination and changes as may be necessary. By combining the fuse element with the switch element, the fuse retaining clip is swung outward away from the line conductors at the time the switch is opened and 45 all manipulations necessary for the replacement of the fuse may be carried on at a safe distance from the live transmission conductors at the top of the pole. The fuse may 50 consist of a glass tube provided with metal ferrules suitably attached to each end, the fuse wires being attached to the ferrule in passing through the tube or other special fuses of suitable size and construction may 55 be used.

The structure can be used, either indoors or outdoors and if they are for outdoor use, the bearing supports for the rock shaft are of such type that they will not rust or 60 "freeze" after being exposed to the weather, under severe conditions. In the construction shown, the cross arm which supports the line also supports the upper element of the switch and only one other cross arm is required, and the two cross arms are tied 65

together in such a way that the entire structure is rigid and secure and perfect alignment of the switch elements is accurately maintained. The construction is cheap to build and to assemble and is rugged in character and the several parts are easily replaceable in case of accident.

If for any reason, the fuse protection is not needed, the fuses and their supporting clips may be removed and a piece of strip copper may be bolted on in place of the fuse, 70 between the fuse caps, and the device then becomes a line sectionalizing switch, serviceable in usual manner and yet reconvertible into a fuse protective device if the need 75 arises.

Although we have herein shown and described one embodiment of our invention, changes and modifications may be made therein without departing from the scope of 80 the invention as defined by the appended claims.

We claim:

1. A combined fuse and switch for use at the top of a pole comprising an upper wood cross arm, stationary clips supported thereon and forming circuit terminals for high voltage line conductors, another wood cross arm on said pole, braces connecting said cross arms to form a rigid structure, a rock shaft carried by said braces and a plurality of switch elements supported by said rock shaft and swinging therewith away from said pole and out of operative connection with said high voltage stationary clips, each 90 of said swinging switch elements including a replaceable fuse.

2. In an electric switch mechanism, the combination with a tubular rock shaft, a counterweighted arm rigidly connected therewith, an insulating push bar operatively connected to said arm to swing said shaft, stationary clips supported above said shaft on a wood cross arm and adapted for connection with high voltage conductors, 100 and swinging members clamped to said shaft and swinging therewith into and out of operative connection with said clips, each 105 of said members comprising a pair of insulators spaced apart and bridged by a fuse, the topmost of said insulators carrying a switch arm connected with the fuse and movable therewith into or out of contact with the stationary clip and the lowermost insulator having means for permanent attachment to a conductor to be protected by 110 said fuse.

3. In a combined fuse and switch for high voltage electric circuits, the combination of 115 a pair of wood cross arms spaced apart at the top of a transmission line pole and connected by three metal strips bolted thereto to form a rigid structure, insulators carried by the topmost arm and bearing stationary clips 120 projecting away from said pole and adapted 125 to

- to form the circuit terminals of a high voltage line, a rock shaft pivotally mounted in said metal strips, a counterweighted arm rigidly connected to said shaft, an insulated 5 push rod connected to said counterweighted arm to swing said rock shaft in its bearings, and switch members supported by said rock shaft and swinging therewith toward the pole to engage said clips, each of said members comprising an arm carrying a pair of insulators spaced apart and bridged by a renewable fuse, one of said insulators carrying a switch arm movable therewith into and out of contact with a stationary terminal 10 of the top cross arm, substantially as described.
4. In an electrical switch mechanism for use on the top of a pole, the combination of a plurality of stationary terminals adapted 15 for connection with high voltage line conductors, a tubular rock shaft, a counterweighted arm connected therewith, a reach bar connected with said arm for controlling

the position of said rock shaft from the base of the pole, means for locking said rock shaft in desired position, and a plurality of switch elements carried by said rock shaft and movable therewith into and out of operative connection with said high voltage terminals, each of said switch elements comprising a rigid arm clamped to the rock shaft, an insulator at either end of said arm, a fuse device bridging said insulators, and a switch arm mounted on the topmost insulator and connected with said fuse device 20 to establish connection with a corresponding terminal when said rock shaft is suitably swung upward toward the top of the pole by means of its reach bar.

In witness whereof, we hereunto subscribe 40 our names this 31 day of May, A. D. 1913.

RALPH ELSMAN.
